WASHING MACHINE

Felix Kellermann, Bronx, N. Y.

Application November 8, 1937, Serial No. 173,301

6 Claims. (Cl. 68—22)

This invention relates to home laundry equipment, and more particularly to washing machines having washing agitator and connected clothes dewatering-mechanism.

5 The invention broadly lies in the concept of a practical and efficient washing machine which is stationary and has direct water supply and drain connections as part of the house plumbing; the invention also contemplates improvements in the 10 design of a combination agitator and wringer mechanism adapted for association with installed washtubs and with those having the aforementioned plumbing connections.

Differently expressed, the invention according 15 to one aspect has to do with an improved construction of a home washing machine in its totality; and according to another aspect it has to do with improvements adapted to permit an existing or installed washtub to be converted into 20 a washing machine of certain desirable characteristics; another aspect is that of space saving.

The invention broadly may be characterized by 25 contrast with the conventional, movable type of washing machine unit now constituting a standard piece of home labor saving equipment. The conventional household washing machine is a unit movable on casters, generally comprising a frame supported tub or vessel or chamber through and from the bottom of which rises the vertical 30 agitator shaft which may be called the oscillator and which is driven from motor-actuated gearing underneath the tub. In a popular category of these machines, and it will herein be called the wringer type, the tub has disposed at its side a 35 wringer post which is operatively connected with the agitator drive mechanism, and because of its location underneath the tub the mechanism may herein be called the underslung type.

The movable unit requires bothersome hose 40 connections for water supply and drainage, and an additional pump for lifting the drainage liquid to the level of an available sink to gain discharge by way of the house plumbing, and this again necessitates moving the machine about and near 45 to a sink; and it also requires a loose cable connection for the motor.

A washing machine installed according to this 50 invention will eliminate potential dripping, leakage, spilling and other inconveniences attendant to the manipulation, operation, function, and upkeep of the aforementioned connections as required in the movable standard unit. Such an installation also avoids potential danger or injury to the operator's toes, which danger is present 55 every time that the relatively heavy movable unit

must be rolled to the place where the aforementioned connections must be made or the machine be used. An installation according to this invention furthermore avoids the phenomena of vibrations, undesirable of themselves and liable to 5 cause a movable machine, especially when filled with water and with wash, to shift bodily from its place of operation as a result of its own vibratory impulses, this being aggravated by any slight slope found to exist in the floors. When 10 unattended the movable unit thus filled and loaded may gather momentum sufficient to result in harmful collision or injury to children or the like.

Further objects are to produce a mechanism 15 through which an installed washtub can be converted into a washing machine of certain desirable characteristics; to design mechanism which is convenient to be so installed with a minimum of labor, and substantially without requiring disturbance, relocation, or removal of an existing washtub or of its plumbing connections and appurtenances; and which mechanism can be installed with advantage in crowded or somehow 20 obstructed locations and localities; and which 25 mechanism is capable of diverse adjustments in view of variant tub dimensions and styles.

Another object is to save the space normally occupied by a standard movable washing machine 30 in homes with washtub installation.

Still other objects are to produce a washing 35 machine which is highly practical and efficient as well as sightly, and which in the last analysis is relatively inexpensive.

Some of these objects are realized in a washing machine construction in which a washtub or 40 similar vessel is directly connected with the plumbing and which has in direct association, or directly united therewith, a suitably constructed combination agitator and clothes wringer mechanism of the underslung type that leaves the top 45 of the machine free, substantially unencumbered, and otherwise useful.

In the case of an installed washtub, in order 50 to convert the same, a suitable hole is provided or conditioned substantially in the center portion of the tube bottom, permitting the insertion therethrough and mounting of the agitator arbor.

Furthermore, the mechanism is sectionalized; that is to say, divided into separately mountable 55 sections, and otherwise constructed to meet requirements of adaptation and of adjustment under diverse conditions of tub installations.

The mechanism herein more specifically referred to is a washing agitator-clothes wringer 55

combination as exemplified by one comprising three main operating sections; to wit: an upright agitator arbor section; an upright wringer post section parallel thereto; and a transverse structural section which comprises the drive mechanism proper or gear casing below. A well-known construction of this general type constitutes a preassembled, rigid structure, U-shaped in its general appearance, and in which the component sections once assembled are non-disconnectible, or normally not intended for disconnection.

Thus it is a feature to have the combination agitator-wringer mechanism divided into suitable component sections separately mountable upon the installed tub and structurally associated directly therewith. A method of assembly made possible by this construction is intended to avoid disturbing the setting of the tub or its plumbing connections. The assembly completed, the sections will constitute a construction supported at two points from the tub, namely, from the center of the bottom and from the margin of the tub, and firmly connected with the tub.

According to another feature a combination agitator-wringer mechanism is designed to permit association thereof with an installed tub so that the wringer post can be placed optionally at either side of the tub.

Other features have to do with more specific requirements of adjustability of the mechanism relative to the tub, and with requirements of adaptability with respect to obstructions.

In one embodiment the agitator-wringer mechanism comprises at least two individual although rigidly interconnectable main component sections which when assembled upon the tub are comparable to a U-shaped construction of which one upright shank (agitator arbor) is mounted in the tub bottom, while the other upright shank (wringer post) finds support by engaging or reaching over the top edge portion of the tub. Adjustment means permit to vary the effective length of either of the upright shanks with respect to the tub. The effective distance between the agitator arbor and the wringer post is also variable and adjustable with respect to the tub. Auxiliary clamping means provide additional all around structural stabilization between mechanism and tub. The conventional washtub installed has a square top portion, and the present mechanism is capable of angular adjustment about the tub center, thus permitting to fit one and the same mechanism to tubs of moderately differing widths. The construction allows for positioning the wringer post optionally at either side of the tub, although intermediate positions are considered to be possible, depending upon local conditions or preference; the character of the construction also provides for clearance of existing drain connections and other obstructions, and is thus designed to render unnecessary the disconnection or relocation of existing drains. In the spirit of this invention also, a clutch for disconnecting the agitator shaft is arranged and constructed to permit manipulation thereof from both sides of the mechanism.

The invention possesses other objects and features of advantage, some of which with the foregoing will be set forth in the following description. In the following description and in the claims, parts will be identified by specific names for convenience, but they are intended to be as generic in their application to similar parts as the art will permit. In the accompanying draw-

ings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings in which:

Fig. 1 is a part-sectional elevation of a combination agitator-wringer mechanism assembled upon a tub, showing example features of how to sectionalize the mechanism into components of assembly.

Fig. 2 is an end view of the mechanism of Fig. 1 showing relation to an adjacent drain connection.

Fig. 3 is a schematic plan view indicating range of angular adjustability of the mechanism relative to the tub, and illustrating tentative clearance relation between the mechanism and an adjacent drain connection.

Fig. 4 is a sectional view similar to Fig. 1, except for a modified showing of the means of sectionalization.

Fig. 5 is a side view of the mechanism shown in Fig. 4.

Fig. 6 is a bottom view of the mechanism shown in Fig. 5 and 4 respectively.

Fig. 7 is a detail view of a part that serves in connecting the agitator arbor section with the drive mechanism proper.

Fig. 8 shows the mechanism of Fig. 1 with assembly sections drawn apart, to wit: an agitator arbor section, a wringer post section, and drive mechanism for both.

Fig. 9 shows the modified mechanism of Fig. 4 with assembly sections drawn apart in a fashion somewhat similar to that of Fig. 8.

Fig. 10 illustrates a construction of the mechanism capable of assembly in a manner different from that illustrated in Figs. 8 and 9.

The agitator-wringer mechanism of Fig. 1 is herein shown to be associated, connected or united with a washtub 10 having a bottom portion 11 and sides 12, which tub may be of the square type made of porcelain or the like and usually found installed in homes or intended for home installation in operative connection with the plumbing.

The agitator-wringer mechanism is a structure of what is herein said to be the underslung type due to the location of the driving mechanism below the tub, and of generally U-shaped appearance and which is roughly constituted of two upright sections A and B, and a transverse section C; in other words: an agitator section A, a wringer post section B, and a drive mechanism C.

The agitator section A operates to oscillate a bladed washing agitator member 13 (shown in dotted lines) surrounding and fitting over a tubular member or agitator arbor 14, although driven by the top end portion 15 of an oscillatable agitator shaft 16. The arbor 14 has a flange or shoulder 17 resting upon the inner bottom face of the tub by way of gasket 18, and it furthermore has an externally threaded portion 19 extending through a hole 20 in tub bottom.

From below the tub bottom a flange member 21 engages over the threaded portion 19 and by

way of gasket 22 or the like it sets against the lower side of the tub bottom. The flange member 21 has retaining means such as a split ring 23 and bolts 24, for connection with the drive gear section C. The drive gear section may be of any suitable construction and it may comprise whatever structural component portions or sections should appear desirable. The drive gear section is here shown to comprise a skeleton 5 ton- or base- or casing construction indicated by the numeral 25. The gearing proper is shown to comprise a bevel gear 26 potentially slidable upon the lower free end of the agitator shaft 16; a companion bevel gear 27 fixed upon a horizontal gear shaft 28; a bevel gear 29 fixed upon the opposite end of the shaft 28; an up and down reciprocable gear sector 30 meshing with bevel gear 29 and driven through a connecting rod 31 from an eccentric point 32 on a worm gear 33 rotated by a worm 34 loosely mounted on a shaft 35 driven by electro-motivating means or a motor 36. The casing construction 25 more specifically is shown to have an angular neck portion 37 which accommodates the bevel gears 26 and 27, gear 26 having a bearing or seat 37a in the neck portion 37, and to have positioning or sustaining means such as a lug or protrusion 38 rising from a cover plate 39, which latter forms a removable sloping bottom 40 for the neck portion 37. The horizontal gear shaft 28 has its bearings at 39 and 40 in the casing construction, and the gear sector 30 is pivoted therein at 41, the worm gear 33 at 42, and the motor 36 is mounted to and suspended 43 from a flange portion 43 forming the lower or bottom part of the casing construction.

It will be noted that the mounted construction as described has a two-point support with respect to the tub, namely, from the central portion of the bottom and from the margin of the tub, and that the driving mechanism of section C and motor are firmly held between these two points of support.

The casing construction 25 has connected with it the wringer post section B by way of bearing or bracket portions 44 and 45, the bracket portion 45 in fact to constitute the housing for a worm gear 46 driven from the motor 36 through shaft 35 and a worm 47. The bracket or housing portion 45 is shown to have a depending pocket 48 to accommodate the lower free end of a wringer shaft 49 which is slidably adjustable in the worm gear 46 for reasons hereinafter to be described.

Aside from the wringer shaft 49 just mentioned, the wringer post section B is shown to comprise a tube member 50 which may be adjustably clamped as at 51 in order to be fixed in the bracket portion 45 which serves as its foot. The tube member 50 has at the upper end thereof a bracket 52 adjustably clamped thereto as indicated at 53, which bracket has a hook portion 54 to engage over the top edge portion of the tub. A clamping jaw 54a is adjustably clamped upon the wringer post at a point intermediate its ends, and adapted to engage upon the underside of the tub for all around stabilization of the mounting if desired. A wringer head proper, fractionally shown at 55, is removably attached to the top end portion of the wringer shaft 49 and can be functionally disconnected from the drive by suitable means not shown.

In order to functionally disconnect the agitator from the drive mechanism a clutch device

56 is shown whereby the loosely mounted worm 34 can be connected with, or disconnected from, the motor driven shaft 35. The arrangement of the clutch device is such that it can be manipulated from either side of the gear section C. 5

Fig. 2 is an end view of the mechanism from the motor end thereof, and it illustrates a structurally well-balanced arrangement, and which is laterally compact enough to avoid interference with adjacent drain connections such as indicated at 57 and found to exist in home tub installations to which a mechanism of this type is potentially to be applied. It also illustrates a certain symmetry and compactness of the mechanism in view of the desirability of having the 10 mechanism mounted optionally in diametrically opposite directions, depending upon where the wringer post is wanted, and with regard to potential obstructions, and for other considerations. 20

It then appears from Fig. 3 (which is a diagrammatic plan view) that the total mechanism is angularly adjustable about the agitator axis as a center, and over a tentative range as indicated by the arm 58, while clearing a drain 25 connection indicated at 59. It also appears that tubs of the square type and of moderately differing widths can be fitted with the same size agitator wringer mechanism by reason of such angular adjustment as is illustrated by the indication (in dot and dash) of a slightly wider tub in Fig. 3. 30

Figs. 4 to 7 show a drive mechanism similar to the one shown in Fig. 1, although modified with respect to parts which connect the arbor 35 section with the drive mechanism and with respect to the mode of inter-connection. There is again shown a motor 60, driving a worm 60a over a clutch device 61, the worm meshing with a worm gear 62 from which a connecting rod or 40 link 63 imparts up and down reciprocating movement to a gear sector 64 meshing with a bevel gear 65 fixed on a horizontal shaft 66 the other end of which has fixed thereto a bevel gear 67 meshing with a companion bevel gear 68 shown 45 to be fixed upon the lower end of an agitator shaft 69 extending into and through an agitator arbor 70 which latter is of a construction substantially as described in connection with Fig. 1 and having an exteriorly threaded portion 72. 50

Motor and gears just enumerated in Fig. 4 are cooperatively combined by means of a base or casing construction as shown and which is similar to the one described in Fig. 1, except for a modification which lies in the construction of a 55 cylindrical neck portion 73 constituting a clamping ring having a clamping bolt 74 (see Fig. 6), and which tightens around a cage member 75 having cutouts 75a and engaging upon the threaded portion 72 of the agitator arbor, and 60 has a gasket 76 interposed between it and the tub bottom. The threaded arbor portion is shown to engage upon a shoulder or ledge 77, deformed interiorly of the cage member 75. A detail of the cage member 75 is shown in Fig. 7 65 and has a circumferential groove 78 in which may engage a removable pin 79 or the like (see Fig. 4), to insure proper positioning and meshing of the bevel gears 67 and 68. 75

Fig. 5 is a side view of the mechanism shown 70 in Fig. 4, and in it is visible a clutch handle 80 for agitator operation.

Fig. 6 is a bottom view of Fig. 5.

The mechanism more in particular according to this invention is intended to be sectionalized 75

in view of certain potential obstructions; that is to say, subdivided into component sections that are conveniently and separately mountable upon the tub into a rigid assembly with one another 5 and with the tub.

Accordingly, Figures 8 and 9 show phantom views of the mechanism of Figs. 1 and 4 respectively, with component sections and parts tentatively drawn apart to illustrate various ways 10 of their prospective assembly with one another and with the tub, and for convenience, identical parts are designated by identical numerals as between Fig. 1 and Fig. 8, and between Fig. 4 and Fig. 9 respectively. According to the invention 15 one or more divisions into component sections may be made in the mechanism wherever feasible or desirable, and in a manner to permit section-wise assembly without encountering obstructions from an existing tub installation for instance 20 from supporting means such as the legs 81 thereof or otherwise.

Accordingly, an arrangement of component sections in Fig. 8 comprises substantially the agitator arbor section A, the wringer post section B, 25 and the drive mechanism C. The mode of assembly is substantially self-explanatory from Fig. 8, although it can be said that for instance sections B and C may be pre-assembled or interconnected per se, then to be connected with section A upon 30 the tub; or else arbor section A may be mounted first in self-sustained position with the aid of flange 21, with sections C and B either individually or jointly to follow.

Fig. 9 is to illustrate modes of sectionwise assembly of the mechanism shown in Figures 4 to 35 7. Again, the sections A, B and C constitute tentative individual sections by virtue of which interference with obstructions due to an existing tub installation can be avoided. For the sake 40 of illustrating various modes and systems of assembly the agitator arbor in section A has its flange or shoulder fashioned as a removable nut 82. In this instance some of the potential modes 45 of assembly are: first, to mount section A together with nut 82 and cage member 75 (see Fig. 7) letting sections C and B follow individually or jointly; or to pre-assemble sections A and C without nut 82, then inserting agitator arbor from below through hole in tub and securing with nut 50 82, whereupon the mounting of section B (wringer post) may follow; or else sections B and C are pre-assembled and positioned upon the tub, whereupon the arbor section A with shoulder or nut 82 thereon is inserted from above through 55 hole 82 and screwed into section C.

In distinction from the modes of sectionwise assembly illustrated in Figures 8 and 9, there is shown in Fig. 10 a somewhat modified construction to illustrate still another mode of sectionalizing and assembling the agitator-wringer mechanism. While the mechanism basically is shown to be substantially the same, distinction will be found in that the wringer post section B and the drive mechanism are shown to be a pre-assembled or pre-manufactured unit ready to be positioned upon the tub. The free end of the gear casing is modified in that it terminates in an outwardly threaded rising portion 83 adapted to be positioned in a hole 84, so that a corresponding agitator arbor section 85 may cap and be screwed down upon the threaded portion 83. A jack member or jack screw is shown to be provided at 86 near the wringer post B upon the gear casing to stabilize the mounting if desired. 70 According to Fig. 10 a further division into com-

ponent or sub-component sections is illustrated at 86a which numeral indicates a split across the structural section C' into sub-section C, and C₂, the split being indicated by flange portions 86b and 86c of the respective sub-sections. The motor 86d may be considered as a separately dis-connectible body or else as a part mountable together with sub-section C₂.

I claim:

1. In a home washing machine of the oscillating agitator type, in combination with a washtub provided with a hole in the bottom for the agitator being driven therethrough, and which washtub is adapted for stationary mounting and for drain connection with the house plumbing; an agitator actuating construction adapted for direct structural association with said tub, which construction comprises an agitator arbor section arising within the tub and having agitator shafting oscillatable therein, a post-like section extending at the outside from the bottom portion to the top edge portion of the tub, a transverse section extending between and connected with said arbor section and said post-like section underneath the tub, said actuating construction thus constituting a substantially U-shaped and substantially rigid structure, said transverse section having electro-motivated drive means for oscillating said agitator shafting in the tub by way of said hole in the tub bottom, and discon- 20 nectible means for fixing said actuating construction relative to the tub by way of said hole in the tub bottom; and means for fixing said post-like section relative to the tub, comprising an upper jaw element engaging over the top edge portion and a lower clamping element vertically spaced a distance substantially the height of the tub from said upper jaw element, and effective in conjunction therewith to fix said construction with respect to an upright wall portion of the 30 tub. 35

2. In a home washing machine of the oscillating agitator type, in combination with a washtub provided with a hole in the bottom for the agitator being driven therethrough, and which washtub is adapted for stationary mounting and for drain connection with the house plumbing; an agitator actuating construction adapted for direct structural association with said tub, which construction comprises an agitator arbor section 45 rising within the tub and having agitator shafting oscillatable therein, a section extending at the outside from the bottom portion to the top edge portion of the tub and having an anchoring portion extending over the top edge of the 50 tub, a transverse section extending between and connected with said arbor section and said outside section underneath the tub and having electro-motivated drive means for oscillating said agitator shafting in the tub by way of said hole 55 in the tub bottom, means for fixing said construction relative to the tub by way of said hole in the tub bottom, and stabilizing means effective between the outer lower corner portion of the construction and the tub and cooperative with 60 said anchoring portion in fixing the construction with respect to the tub. 65

3. A home washing machine according to claim 2, in which the stabilizing means comprise a bracing element adjustably connected with said outer lower corner portion of the construction. 70

4. In a home washing machine of the oscillating agitator type, in combination with a washtub provided with a hole in the bottom for the agitator being driven therethrough, and which

washtub is adapted for stationary mounting and for drain connection with the house plumbing; an agitator actuating construction adapted for direct structural association with said tub, which construction comprises an agitator arbor section rising within the tub and having agitator shafting oscillatable therein, a motorized drive gear section connected with said arbor section for oscillating said agitator shafting by way of said hole in the tub bottom, and extending towards the margin of the tub, and a clamping device connected with the free end of said driving section and having an upper and a lower clamping jaw portion engaging over and under an upstanding wall portion of the tub.

5. In a washing machine of the oscillating type, in combination with a washtub provided with a hole in the bottom for the agitator being driven therethrough, and which washtub is adapted for stationary mounting and for drain connection with the house plumbing, an agitator actuating construction adapted for direct structural association with said tub, which construction comprises a substantially vertically disposed section extending at the outside substantially from the bottom portion to the top edge portion of the tub and having an anchoring portion extending over the top edge of the tub, a transverse section connected with the lower end por-

tion of said outside section and extending underneath the tub and having a casing in which driving elements operate, and having electro-motivating means for said drive elements, an oscillatory member driven by said driving elements and disposed to be effective by way of said hole in the tub bottom, disconnectible securing means provided to be effective by way of said opening in the tub bottom between the tub bottom and said transverse section, stabilizing means cooperative 10 with said anchoring portion and effective between the outer lower corner portion of the tub and said agitator actuating construction for fixing the intermediate portion thereof with respect to the tub, means effective between said oscillatory member and said casing and adapted to prevent escape of water into the casing, and an agitator member operatively connected with said oscillatory member.

6. Washing machine according to claim 5, with 20 the addition of a clutch device associated with said driving elements for controlling the driving connection with said oscillatory member, and means disposed at either side of said transverse section and thereby operable for manipulating 25 said clutch device optionally from either side of the transverse section.

FELIX KELLERMANN.
